UNITED STATES PATENT OFFICE.

LESTER F. PHILLIPS, OF CHICAGO, ILLINOIS.

FASTENING DEVICE.

Application filed July 2, 1924. Serial No. 723,784.

This invention relates to fastening devices of that type in which interlocking members are secured to two flexible elements in staggered relation, whereby upon movement of 5 these elements towards each other to approximately parallel relationship said members are brought into interlocking engagement so as to prevent the flexible parts from accidentally leaving the parallel relationship 10 into which they have been placed.

It is an object of the invention to improve the engagement of the interlocking members by providing each of them with a plurality of interlocking projections and indentations 15 on each surface to patentably differ from similar fastening devices in which a single projection is provided on one side of an interlocking member to enter into engagement with an indentation or socket on the adjacent surface of the next interlocking member.

It is also an object of the present invention to improve the attachment of the fastening members to the flexible elements and 25 to make provision for properly spacing the interlocking members on the flexible elements.

With these and with numerous other objects in view, various embodiments of the 30 invention are illustrated in the accompanying drawings and described in the following specification.

In the drawings:

Fig. 1 is a front elevation of a fastening 35 device of this character;

Fig. 2 is a similar elevation, showing a slide and certain interlocking members in section;

Fig. 3 is an enlarged horizontal section on 40 line 3—3 of Fig. 1;

Fig. 4 is a section on line 4—4 of Fig. 1 through the slide for actuating and releasing the interlocking members;

Fig. 5 shows perspective one of the 45 members with projections and indentations on each side;

Fig. 6 is a perspective view of a spacing member;

Fig. 7 shows in perspective a modified 50 embodiment of one of the interlocking members;

Fig. 8 is a perspective view of two modified members in interlocking relation;

Fig. 9 is a detail sectional view through 55 a portion of a flexible element with a plu-

rality of interlocking members and spacers, and

Fig. 10 is a similar detail sectional view and part elevation of a flexible element integral with the spacing devices. 60

In Figs. 1 and 2 the fastening device is shown in connection with marginal portions of an opening to be closed thereby. These marginal portions 1 support the fastening device by means of strips 2 of cloth or the like. The strips 2 which are sewed to the marginal portions are folded on themselves so as to form near the fold a tubular part 3 through which the flexible element 4 is inserted. Serially disposed on the cloth covered element 4 are in alternation the interlocking members 5 and the spacers 6. The interlocking members or clips 5, as shown in Figs. 1 to 3 and 5, inclusive, are short bars of metal terminating at one end in bifurcated portions 7 adapted to be clamped about the cloth covered flexible elements 4. 70

Opposite surfaces of this clip 5 are each provided with a plurality of interlocking portions. The interlocking portions on each side are formed by a projection 9 and an indentation 10 respectively, the projection on one side being directly opposite to the indentation on the other side, and vice versa. 80 It will be seen, therefore that each of these members projects by means of the teats 9 into companion members on both sides thereof, while each of the members is entered by projecting teats of members also located at opposite sides thereof, whereby 90 a complete interlocking of adjacent members 5 is attained when the flexible elements 4 to which these members 5 are secured are moved to parallel relation, as indicated in the lower part of the device shown in Figs. 95 1 and 2.

A slide 11 for positively bringing the flexible elements 4 to parallel relation, or for spreading them to facilitate the opening of the fastening device respectively, is shown 100 in Figs. 1 to 4. It comprises a sheet metal part having a central branch 12 and two angularly extending branches 13, of substantially tubular form, but open at the sides, so as to be slidable along the margins of the opening which the fastening device is to close. Above the angular branches 13 the front and rear wall of the slide are fastened to each other by a rivet 14 or the like. 105 At this upper end the sheet metal of which 110

the slide in made is formed into a sleeve 15 serving for pivotally receiving a locking tongue provided with angularly projecting lugs 18 at each side thereof which are adapted to enter through the staggered openings 19 into the interior of the slide 11, when the tongue is in holding position.

Owing to the arrangement of these lugs 18, the slide 13 is prevented from dropping 10 towards one end of the marginal opening after, its movement towards the other end, owing to the fact the flexible elements have been moved towards each other over their entire length, and the locking members 5 15 below the slide have been moved to interlocking relation, since the lugs then rest on two of these interlocking members. When the slide 11 is moved upward, the tongue 16 having then been released from engagement 20 with members 5, the lower portion 12 of the slide brings the flexible strings 4 into parallel relation.

When it is desired to open the fastening device the tongue 16 is swung about its 25 pivotal mounting so that the projections 18 leave the offset openings 19 in the slide, and the slide is moved downward again so as to change the relation of the elements 4 from approximately parallel to an angular relation, forcing the locking members to release 30 position.

As long as the prongs 18 project inward, as indicated in Fig. 4, so as to extend between adjacent fasteners, a displacement of 35 the slide cannot be effected therefore the fastening device is maintained locked up to that point to which the slide 11 has been adjusted.

For the purpose of maintaining the individual clips properly spaced on the flexible elements 4, spacers or collars 6 are inserted between each two fasteners on each element 4 in such manner that the clips on each element are staggered relatively to those 45 on the other element.

A modification of a clip, also having on each operative surface at least one projection and an indentation, so as to attain a double locking effect with the fastening clip 50 above, as well as with the fastening clip below the same is illustrated in Fig. 7 where the clip is shown as a stamping made of sheet metal.

A strip of sheet metal 20 is folded transversely midway of its length, and the ends which are thereby brought into superposition are bent so as to form a fork or partly open cylindrical member 21 having its axis at right angle to the axis of the strip. The 55 opposite longitudinal edges of the strip 20 are provided with projecting spurs or spikes 22, which upon the folding of the strip transversely about its middle are brought into alignment so as to form single projections 9' 60 serving the same purpose as the projections

9 of the clip first described. By a suitable tool the two portions of the folded strip are pried apart directly in opposition to the spikes 9' so as to produce on each strip portion a bight 23, the bights 23 supplementing 70 each other to form a socket 10'.

This strip is retained in folded relation by the provision of a lateral extension 24 projecting from one of the longitudinal edges 75 of the strip, and bent around the formed clip so as to prevent the opening or unfolding of the same, as indicated in Fig. 7.

Another modified clip is illustrated in Fig. 8 in which two fastening elements are shown to be in interlocking relation.—each of the clips 30 and 30' are also being made of a sheet metal stamping. The manufacture of this particular modification is extremely simple and cheap,—at the same time, however, sufficiently effective to prevent accidental loosening of any of the parts after they have been placed into interlocking relation.

A strip of metal is provided near one end with an elongated opening whereby upon folding it about the transverse axis central of said opening to the extent indicated at 31, a notch 32 is formed which is adapted to attach the clip to a flexible element 4. The notch 32 formed in this way is arranged to partly embrace the flexible element 4 and 90 can easily be clamped to it.

The main portion of the clip extending from the notch 32 is cut transversely near the opposite end into aligned slits extending from opposite longitudinal edges, and terminate a short distance transversely of the longitudinal axis of the clip. The portions of the strip or clips located at opposite sides of each slit are then bent about the longitudinal axis in opposite directions, the pairs 105 of marginal parts of each portion project in the same direction, so that, for instance, the marginal parts 33 on one side of a slit are bent downward while the marginal part 34 at the opposite side of the same slit are 110 bent upward.

Owing to this deformation of the strip there are produced two upwardly extending prongs 34 on one surface of the strip and two downwardly extending portions, of which only one of the prongs 33 is visible (Figure 8). Between these prongs 34 and similarly between the other two prongs 33 there is formed an indentation serving for permitting the entry of cooperative locking 115 portions of adjacent similar clips, one of which is indicated at 30', Fig. 8. The outer prongs of clip 30, therefore, cooperate with the inner prongs of the adjacent clip 30' and the inner prongs located closer to the head 31 of the clip 30 cooperate with the outer prongs of the adjacent clip 30'. In this way a plurality of fastening projections or indentations respectively extend 120 from each side of each clip to interlocking 125 130

engagement with the adjacent clip above and below the same.

In Fig. 10 a flexible element 40 is shown in which the spacers 41 for interlocking members are formed integral with the element itself, the element being constructed as a wire having at spaced intervals enlargements 41 between which the interlocking members are mounted so as to be held against axial displacement relatively to the element.

I claim:

1. In a device of the character described, a pair of flexible members, a series of interlocking members arranged on each of said flexible members, the individual locking members of each series being spaced apart complementally and adapted to operatively engage the interlocking members of the other series, and spacing elements on said flexible members and disposed between and abutting adjacent interlocking members of both series of interlocking members.

2. A fastening device of the type in which a pair of flexible elements are provided with interlocking members, including on each of the interlocking members and on each side thereof an indentation and a projection alternately arranged and adapted for cooperation with projections and indentations respectively of companion interlocking members adjacent the opposite sides of said first named interlocking member.

3. A fastening device comprising a pair of flexible elements, interlocking members serially disposed thereon, the members on one flexible element being staggered in relation to the members on the other flexible element and being adapted for engagement with adjacent interlocking members disposed on said other flexible element, and spacing devices on each of said flexible elements between and abutting adjacent ends of said members.

4. A fastening device comprising a pair of flexible elements, interlocking members secured by one end to the flexible elements, a slide partly embracing each of said flexible elements and adapted upon movement to bring said flexible elements into approximately parallel relation to cause the interlocking members to enter into interlocking relation, and means engaging simultaneously at a plurality of points between adjacent interlocking members and adjacent said

flexible elements for locking said slide in any desired position in the series of interlocking members.

5. A fastening device comprising a pair of flexible elements, interlocking members secured at one of their ends to each of said elements and adapted to enter into interlocking relation, a slide movably connected with both of the flexible elements and having a plurality of openings, and a tongue pivoted to the slide and provided with a pair of lugs adapted to enter thru said openings to be disposed between two of the interlocking members associated with the same flexible element.

6. A fastening device comprising a pair of flexible elements, interlocking members serially arranged on each of said elements, each of said interlocking members being provided on its upper and lower surface with socket portions and projecting portions adapted to coact respectively with projecting portions and socket portions of the next adjacent members both above and below, each of said portions being formed from a strip of metal bent back upon itself.

7. A fastening device comprising a pair of flexible elements, each of the elements being provided with enlargements at spaced intervals and interlocking members secured to each of said flexible elements intermediate two enlargements on said flexible elements, whereby said enlargements prevent axial displacement of the interlocking members relatively to the flexible elements said interlocking members being similarly shaped and each having a direct interlocking engagement with the adjacent members on both sides.

8. A fastening device comprising a pair of flexible elements, two series of interlocking members each member of each series being secured at one end thereto in staggered relation, with respect to those of the other series, a slide partly embracing the flexible elements and forming a substantially permanent part of the fastening device, and a stop member pivotally mounted on the slide for locking the fastening device having means on each side thereof for engaging interlocking members of the two series.

In testimony whereof I affix my signature at 7 South Dearborn St., Chicago, Illinois.
